UNITED STATES PATENT OFFICE.

WILLIAM ROBERTSON, OF ERIE, PENNSYLVANIA, ASSIGNOR TO LOVELL MANUFACTURING COMPANY, OF ERIE, PENNSYLVANIA, A CORPORATION OF PENNSYLVANIA.

CLOTHES WRINGER.

Application filed February 25, 1922. Serial No. 539,111.

It is desirable to supply wringers with a support adjacent to the bite of the rolls both for guiding the clothes to the rolls and for a hand support for the operator in spreading and adjusting the clothes to the rolls. Supports of one type or another have heretofore been used but they have been in the form of rollers, or in the form of stationary plates secured to the frame. With these devices clothes which may become caught on the wringer roll and thus wound with the roll come against the unyielding bar or support and thus injure the clothes. One of the objects of the invention is to provide a support which will yield and prevent this result. Wringers are usually supplied with drip boards and as wringers are now ordinarily made these drip boards are reversible, particularly for power wringers. While these drip boards do accomplish very largely the purpose for which they are designed more or less water is carried over the ends of the boards and over the rear side of the board. I have provided means for preventing this in the form of gates, preferably pivotally mounted and hung on the supports so that the board may be readily reversed without attention to these gates.

The invention is illustrated in the accompanying drawings as follows:

Fig. 1 shows an elevation of a wringer, a part of the frame being broken away to better show construction.

Fig. 2 is a section on the line 2-2 in Fig. 1.

1 marks the frame, 2 the upper roll, 3 the lower roll, 4 the upper shaft, 5 the lower shaft, 6 a gear on the upper shaft, 7 a gear meshing with the gear 6, and 8 a crank for driving the roll, it being understood, however, that for the ordinary washing machine the driving connection is substituted for the crank. The upper shaft is mounted in bearings 9 and the lower shaft is mounted in bearings 10, the upper bearings being movable in the frame in the usual manner. Springs 11 exert pressure on the upper bearings and these are engaged by a cross bar 13, the cross bar being adjusted by the usual screw 14.

The drip board 15 has the upturned edges 16, these edges being provided with slots 17. Pins 18 extend through the slots 17 into the frame and form a means of sup-

port for the drip board. This is a common construction, the slot permitting the drip board to be moved along the pin so as to reverse the drip board, the drip board swinging to reverse inclinations as the drip board is moved to bring the opposite ends of the slot into engagement with the pins.

A supporting bar 19 is mounted adjacent to and below the bite of the rolls. This bar is yieldingly mounted preferably by having the arms 20 extend upwardly from the ends of the bar, these arms being pivotally secured to ears 21 on the frame by pins 22. These supports are ordinarily provided at the front and rear of the wringer so as to provide for the reverse action of the wringer. It will be seen that these supporting bars 19 are free to swing outwardly from the rolls and thus to clear any clothes or other material that may be wound on to the roll.

A gate 23 is pivotally mounted on hooks 24 extending from the bottom of the support 19. There is preferably one of these gates on each support and there is one at the front and one at the rear of the rolls. The gate at the front of the roll will hang practically free and perpendicularly allowing sufficient space for the water to discharge under it and at the same time it checks the water so as to prevent it splashing over the edges 16. The gate at the rear of the wringer is swung to an inclination as the board is tilted and tends to prevent any discharge of water over the rear end of the board. These gates are so hung as to permit the free swinging of the drip board without attention of the operator as clearly shown in Fig. 2.

What I claim as new is:

1. In a clothes wringer, the combination of a frame; rolls mounted on the frame; a reversible inclined drip board mounted in the frame below the rolls, said board extending in a single plane through the frame and beyond the plane of the face of the rolls at both sides of the frame; and pivotally mounted gates carried by the frame at the sides of the wringer the gate at the high side of the board extending downwardly into sufficiently close relation with the drain board to prevent movement of water toward the high side of the board.

2. In a clothes wringer, the combination of

a frame; rolls mounted in the frame; a reversible drip board mounted in the frame below the rolls; and gates at the front and rear of the rolls, said gates being pivotally mounted and carried by the frame and extending downwardly into sufficiently close relation with the board to prevent the movement of water toward the high side of the board.

10 3. In a clothes wringer, the combination of a frame; rolls mounted in the frame; a reversible drip board mounted in the frame below the rolls; and gates at the front and rear of the rolls, said gates being pivotally mounted and carried by the frame, and extending downwardly into close relation with the board, the gate at the rear having its bottom resting on the board and inclined toward the same side of the wringer as the board.

15 4. In a clothes wringer, the combination of a frame; rolls mounted in the frame; a drip board mounted in the frame below the rolls; a support pivoted to the frame; and a gate pivotally mounted below the bite of the rolls carried by the support and extending down-

wardly sufficiently close to the drip board to prevent movement of water toward the high side of the board.

5. In a clothes wringer, the combination 30 of a frame; rolls mounted in the frame; a drip board mounted in the frame below the rolls; a support pivotally mounted on the frame; and a gate hung on the support and extending downwardly into close relation 35 with the board.

6. In a clothes wringer, the combination 40 of a frame; rolls mounted in the frame; a reversible drip board mounted in the frame below the rolls; supports arranged at the front and rear of the rolls adjacent to and below the bite of the rolls; a pivotal mounting for the supports; and gates pivotally mounted and hung on 45 said supports, said gates extending downwardly to the drip board and permitting the free swinging of the drip board as it is reversed.

50 In testimony whereof I have hereunto set my hand.

WILLIAM ROBERTSON.
